US00D852799S

(12) **United States Design Patent** (10) **Patent No.:** **US D852,799 S**
(45) **Date of Patent:** **** Jul. 2, 2019**

(54) **PORTABLE DEVICE CORNER**

(71) Applicant: **Fairhaven Group, Inc.**, Seattle, WA (US)

(72) Inventors: **Timothy John Fenton**, Mercer Island, WA (US); **Gary Allen Ashley**, Seattle, WA (US)

(73) Assignee: **PIONEER SQUARE BRANDS, INC.**, McLean, VA (US)

(**) Term: **15 Years**

(21) Appl. No.: **29/555,317**

(22) Filed: **Feb. 19, 2016**

(51) **LOC (11) Cl.** **14-03**

(52) **U.S. Cl.**

USPC **D14/440**; D14/250

(57) **CLAIM**

The ornamental design for a portable device corner, as shown and described.

DESCRIPTION

FIG. 1 is a front perspective view of a first embodiment of a portable device corner, showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a front perspective view of a second embodiment of a portable device corner, showing our new design.

FIG. 7 is a front elevational view thereof.

FIG. 8 is a rear elevational view thereof.

FIG. 9 is a left side elevational view thereof; and,

FIG. 10 is a right side elevational view thereof.

The features shown in broken lines in the drawing figures depict features that form no part of the claimed design.

1 Claim, 4 Drawing Sheets
